UNITED STATES PATENT OFFICE.

JOHN GEARY, OF PHILADELPHIA, PENNSYLVANIA.

ELECTRICAL PUSH-BUTTON.

SPECIFICATION forming part of Letters Patent No. 320,238, dated June 16, 1885.

Application filed April 15, 1884. (No model.)

To all whom it may concern:

Be it known that I, JOHN GEARY, a citizen of the United States, residing at Philadelphia, in the county of Philadelphia and State of Pennsylvania, have invented certain new and useful Improvements in Electrical Push-Buttons; and I do hereby declare the following to be a full, clear, and exact description of the invention, reference being had to the accompanying drawings, which form part of this specification, in which—

Figure 1 is a vertical or transverse section. Fig. 2 is an inverted plan. Fig. 3 is a perspective of staple. 15 My invention has for its object to provide an electrical "push-button," which in operation shall have rubbing or sliding contacts, whereby the points of contact will be kept clean and insulation from dust, &c., avoided. 20 A further object of my invention is to provide an electrical push-button which shall be simple in construction and comparatively inexpensive, yet durable, efficient, and not liable to get out of order. 25 My invention consists in the peculiar construction and combinations of parts hereinafter fully set forth and claimed.

Referring to the accompanying drawings, A represents an insulating-base in the form of 30 a ring, and B a metal cylinder or cap attached thereto. If desired, parts A and B may be integral and consist of insulating material.

C is a button or disk designed and adapted to fit in the cylinder B and to be moved in 35 and out in the latter. On the inner or under side of this button or disk, and between the latter and the shoulder *a* of the ring A, is a spiral spring, D, which tends to press said button outwardly or upwardly, and which will 40 yield to pressure and permit said button to be pushed inwardly or downwardly.

To the inner side of said button C is secured, by a screw, *e*, or equivalent fastening, a metallic spring-staple, E, of approximately U 45 shape, having two limbs or branches, *e* *e*. The outer extremities of these limbs converge toward each other, as shown at *e* *e*, not meet-

ing, however, when the button is in its normal outward position. These extremities are adapted and designed to establish metallic connection between the electrodes or battery-terminals *f* *f*', which latter are shown as wires passing into the base A. When the button C is pushed inwardly, the ends *e* *e* are brought into contact with said terminals *f* *f*', sliding and rubbing thereon in the act of forming contact, thus operating to keep the contacting surfaces clean and bright.

To keep the button and its attached parts from coming out of place, one of the legs of the staple E is provided with a lug or stop, *e*', which abuts against a transverse pin, *g*, inserted in the base, and to keep the button from being pushed in too far, another lug or stop, *e*°, may be formed on one of the legs of the staple E, the pin *g* thus coming between said two lugs or stops, which latter are plainly illustrated in Fig. 3.

It is obvious that when the button is pushed in, electrical connection is established between the battery-terminals through the staple E, and that when pressure is relieved the button is impelled outwardly by spring D, electrical disconnection being thus effected and the legs of the staple springing apart.

What I claim as my invention is as follows:

1. The combination, in an electrical push-button, of base A, cylinder or cap B, button C, spring D, spring-staple E, having converging ends *e* *e*', and naked wires *f* *f*', which pass through holes in said base and are permanently secured therein, substantially as shown and described.

2. In an electrical push-button, the combination, with spring-staple E, having a lug, *e*' or *e*°, of transverse pin *g* in base A, substantially as shown and described.

In testimony that I claim the foregoing I have hereunto set my hand this 10th day of April, 1884.

JOHN GEARY.
